ATTORNEY.

UNITED STATES PATENT OFFICE

NATHAN H. BERGSTROM, OF NEENAH, WISCONSIN

PULP DISTRIBUTOR

Application filed July 14, 1930. Serial No. 467,835.

The present invention relates in general to improvements in the art of manufacturing sheet material such as paper, and relates more specifically to improvements in the construction and operation of devices for distributing fluent substances such as a mixture of fibrous material and liquid, over the transporting surface of a conveyor such as the wire cloth or screen of a Fourdrinier.

10 A general object of the invention is to provide an improved device for distributing fluent material over an advancing surface by which the material is being transported.

It is customary in the art of manufacturing paper and the like, to provide a so-called Fourdrinier comprising a screen or wire cloth conveyor having a constantly advancing material transporting and liquid drainage portion, and a feeder for delivering the pulp or 20 mixture of fibrous material and liquid to the advancing screen portion in the form of a layer or film of regulable thickness. It has been found that the fluent mixture after leaving the feeder, does not remain at its initial 25 level or thickness, and when treating certain kinds of stock, it is impossible with the ordinary feeder to insure uniform distribution of the material over the entire screening area, thereby producing inferior final product.

30 It is a more specific object of the present invention to provide simple apparatus for effectively eliminating this defect of the prior paper making machinery, whereby the fluent mixture or pulp may be uniformly distributed 35 over the transporting screen, regardless of the characteristics of the pulp. Another specific object of the invention is to provide means for effecting convenient adjustment of 40 the distributor so as to permit advantageous utilization thereof under various conditions. These and other objects and advantages will appear from the following detailed description.

45 A clear conception of an embodiment of the invention and of the mode of constructing and of operating devices built in accordance therewith, may be had by referring to the drawings accompanying and forming part of 50 this specification in which like reference char-

acters designate the same or similar parts in the several views.

Fig. 1 is a vertical section on the line 1—1 of Fig. 2, through a fragment of a sheet forming machine of the type customarily used in the manufacture of paper, the machine having several of the improved distributors associated therewith; and

55 Fig. 2 is a top view of the apparatus shown in section in Fig. 1.

60 Referring to the drawings, the sheet forming machine which is of ordinary construction, comprises in general a wire cloth or perforated band conveyor 3 which is constantly movable upon rotary supports including a breast roll 4, rotatably mounted in adjustable bearings carried by a main frame 5. The conveyor 3 co-acts with one or more adjustable tensioning rollers 16 also supported by the frame 5, and has an upper material 65 transporting and drainage portion co-acting with a series of parallel table rolls 6. A pulp feeder 7 comprising an adjustable feed plate 8 is adapted to deliver fluent material such as fibrous pulp through a discharge opening 70 75 in the form of a layer of variable thickness upon the upper constantly advancing portion of the conveyor 3. Disposed directly above the material advancing portion of the conveyor 3, is a series of elongated distributor plates 10, each having a lower edge cooperable with the material being transported by the conveyor 3, to uniformly distribute the said material over the upper conveyor 80 surface. Each of the plates 10 is adjustably 85 supported upon a series of cross bars 11, by means of a plurality of threaded supporting rods 12 having clamping nuts 13, 14 associated therewith, the rods 12 being independently laterally adjustable within slots 15 90 formed in the supporting bars 11. The plates 15 extend away from the feeder opening 9 in the direction of advancement of the conveyor 3, and each of the plates 10 is deflectable 95 in the manner indicated in Fig. 2.

During normal operation of the paper making machine, the conveyor 3 is being advanced in a manner to cause the upper material transporting portion thereof to move away from the feeder discharge opening 9. 100

The pulp is delivered from the feeder 7 through the opening 9 and upon the upper run of the conveyor 3 in the form of a continuous layer of width approximating that of the conveyor belt. As the layer of pulp is advanced over the table rollers 6, the liquid is drained from the fibrous material constituting the pulp mixture, and the relatively dry sheet of fibre is subsequently treated in 10 suitable machinery to produce the final paper. While the thickness of the layer of pulp delivered from the feeder discharge opening 9 may be relatively uniform at the time of such delivery, this thickness frequently 15 changes as the layer is advanced by the conveyor 3, and such variation in thickness is detrimental to the production of a uniform final product. In order to eliminate such variation in thickness of the layer and consequent production of inferior final product, 20 the distributors 10 may be set to uniformly distribute the pulp being advanced by the conveyor, during the drainage of liquid therefrom, thus insuring the production of 25 paper of uniform quality.

The position of each plate 10 may be readily varied by manipulation of the nuts 13, 14. These nuts 13, 14 and the supporting rods 12 not only permit lateral adjustment and deflection of the distributor plates 10, but also 30 permit vertical adjustment thereof in order to accommodate different thicknesses of layers being transported by the conveyor 3. It will also be apparent that any number of 35 these distributor plates 10 may be provided, and that these plates 10 may be formed of any suitable material especially adapting them for their intended purpose.

It should be understood that it is not desired to limit the present invention to the exact details of construction and to the precise mode of operation herein shown and described, for various modifications within the scope of the claims may occur to persons 45 skilled in the art.

It is claimed and desired to secure by Letters Patent:

1. In combination, a conveyor having a material transporting surface, means for feeding a mixture of fibrous material and liquid upon said conveyor surface during advancement thereof, and a normally stationary adjustable plate extending in the general direction of travel of said conveyor, said plate 50 cooperating with said surface to distribute said material thereover.

2. In combination, a perforated conveyor, means for feeding a mixture of fibrous material upon said conveyor during advancement 60 thereof, and means having an edge extending in the general direction of advancement of said conveyor and cooperating therewith to distribute said mixture thereover before drainage of the liquid through the conveyor 65 perforations.

3. In combination, a perforated conveyor, means for feeding a mixture of fibrous material upon said conveyor during advancement thereof, and a plate adjustably supported above and having an edge cooperable with 70 and extending in the general direction of advancement of the transporting surface of said conveyor to distribute said mixture over said surface before drainage of the liquid through the conveyor perforations. 75

4. In combination, a perforated conveyor, means for feeding a mixture of fibrous material upon said conveyor during advancement thereof, and a series of laterally adjustable plates supported above and each having an 80 edge cooperable with and extending in the general direction of advancement of the transporting surface of said conveyor to distribute said mixture over said surface before drainage of the liquid through the conveyor 85 perforations.

5. In combination, a conveyor having a perforated material transporting portion, a feeder for delivering a layer of mixture of fibrous material and liquid upon said conveyor portion, and means comprising an elongated edge extending away from the delivery opening of said feeder and in the general direction of advancement of said conveyor portion to subsequently uniformly distribute 90 said mixture over said portion before drainage of the liquid therefrom. 95

6. In combination, a perforated conveyor, a feeder for delivering a layer of mixture of fibrous material and liquid upon said conveyor, and a plate adjustably supported above and having an edge cooperable with and extending in the general direction of advancement of the transporting surface of said conveyor to subsequently uniformly distribute 100 said mixture over said conveyor before drainage of the liquid through the conveyor perforations. 105

7. In combination, a wire cloth conveyor, a feeder for delivering a layer of mixture of fibrous material and liquid upon the transporting surface of said conveyor, a plurality of plates extending away from said feeder in the general direction of travel of said conveyor, said plates presenting distributing edges disposed in close proximity to said conveyor surface, and means for effecting independent adjustment of each of said plates. 110 115

8. In combination, a wire cloth conveyor, a feeder for delivering a layer of mixture of fibrous material and liquid upon the transporting surface of said conveyor, a plurality of plates extending away from said feeder in the direction of travel of said conveyor, said plates presenting distributing edges disposed in close proximity to said conveyor surface, and means for effecting both vertical and horizontal adjustment of each of said plates. 120 125

9. In combination, a conveyor having a 130

material transporting surface, a feeder for delivering a layer of fluent material upon said conveyor surface, means for adjusting said feeder to vary the thickness of said layer, a plate extending in the general direction of advancement of said conveyor for subsequently distributing said material uniformly over said surface, and means for adjusting said plate to cooperate with layers of material of varying thickness.

10 10. In combination, a perforated conveyor, a feeder adjustable to deliver layers of pulp of various thicknesses upon said conveyor, a series of plates for subsequently uniformly distributing said pulp over said conveyor, and means for effecting both vertical and horizontal adjustment of each of said plates.

15 11. In combination, a conveyor having a material transporting surface, means for feeding a mixture of fibrous material and liquid upon said conveyor surface during advancement thereof, and a normally stationary vertically and laterally adjustable plate extending in the general direction of travel of said conveyor, said plate cooperating with said surface to distribute said material thereover.

20 12. In combination, a perforated conveyor, means for feeding a mixture of fibrous material upon said conveyor during advancement thereof, and means having a vertically and laterally adjustable edge extending in the general direction of advancement of said conveyor and cooperating therewith to distribute said mixture thereover before drainage of the liquid through the conveyor perforations.

In testimony whereof I affix my signature.
